CLAIM

The ornamental design for an ice and snow scraper, substantially as shown and described.

DESCRIPTION

FIG. 1 is a perspective view of an ice and snow scraper showing our new design;

FIG. 2 is a bottom plan view thereof;

FIG. 3 is a side elevation thereof.

The side of the scraper which is not shown is a mirror image of the side disclosed in FIG. 3.

FIG. 1

FIG. 2

FIG. 3
